UNITED STATES PATENT OFFICE

ERNEST KUHNE, OF NEW YORK, N. Y.

CIGAR-MACHINE.

SPECIFICATION forming part of Letters Patent No. 742,877, dated November 3, 1903.

Application filed July 10, 1903. Serial No. 164,943. (No model.)

To all whom it may concern:

Be it known that I, ERNEST KUHNE, a citizen of the United States, residing at New York city, Manhattan, county and State of New York, have invented certain new and useful Improvements in Cigar-Machines, of which the following is a specification.

This invention relates to a cigar-machine by which a bunch is uniformly shaped and a wrapper is simultaneously rolled around the bunch from tip to stub.

In the accompanying drawings, Figure 1 is a plan of my improved cigar-machine, showing it closed; Fig. 2, a similar view showing it open; Fig. 3, a cross-section on line 3-3, Fig. 1; Fig. 4, a cross-section on line 4-4, Fig. 1; Fig. 5, a cross-section on line 5-5, Fig. 1; Fig. 6, a longitudinal section of one of the rollers having enlarged ends, and Fig. 7 a similar section of one of the rollers having reduced ends.

The letters *a* and *b* represent the upper and lower sections of a divided frame open at the top and connected by a hinge *c*, so that the upper frame-section or cover *a* may be readily swung up or down upon the lower frame-section or base *b*. Within each frame-section are hung three parallel rollers, the six rollers of both sections being so grouped as to form a cigar-shaped chamber or mold between them.

In order to obtain the shape desired, two forms of rollers are used—viz., three rollers *d*, having expanded ends, and three rollers *e*, having contracted ends, the rollers *d* and *e* alternating with each other. As seen in Fig. 6, the roller *d* has one gradually expanded or thickened end *d'*, conforming to the tip end of the cigar, and one abruptly expanded or thickened end *d''*, conforming to the stub end of the cigar. Each roller *e*, Fig. 7, has one gradually-reduced end *e'*, conforming substantially to the end *d'*, and one abruptly-reduced end *e''*, conforming substantially to the end *d''*. When the frame *a* *b* is closed, Fig. 3, and the rollers *d* *e* consequently assume their working position, the adjoining rollers will thus act as complements to one another and form a central cigar-shaped mold for the reception of the "bunch" *f*. The six rollers *d* *e* are all rotatable simultaneously in the

same direction, to which effect their shafts *d*³ *e*³ carry clutch-jaws *d*⁴ *e*⁴. The jaws *d*⁴ *e*⁴ are adapted to be coupled to clutch-jaws *g*' *h*', mounted on shafts *g* *h*. The six shafts *g* *h* 55 are journaled in a bearing or box *i* and are arranged in horizontal alinement with the six shafts *d*³ *e*³, respectively. The shafts *g* *h* are rotated by hand or power, the drawings showing the latter construction. Here the driving-shaft *j*, having pulley *j'* and journaled in box *i* centrally between the shafts *g* *h*, carries two pinions *j*² *j*³. The pinion *j*² inter-gears with the three pinions *g*² of shafts *g*, while the pinion *j*³ inter-gears with the three 65 pinions *h*² of shafts *h*.

In order to throw the clutches into or out of engagement, either the frame *a* *b* or the box *i* should be made slideable. As shown in the drawings, the box *i* is rigidly mounted 70 upon a bed-plate *k*, having a pair of longitudinal rails *k'*, that engage grooves *b'* of the slideable base *b*.

In use the frame *a* *b* is moved away from box *i*, Fig. 2, so that the clutches are uncoupled, the cover *a* is thrown back, and a bunch of tobacco *f* is placed into the mold formed between the rollers *d* *e*. The cover *a* is then swung down, and the sections *a* *b* are moved toward box *i*, Fig. 1, so that the 80 clutches are coupled, and the rollers *d* *e* are thereby operatively connected to the driving-shaft *j*, which will now rotate all six rollers simultaneously in the same direction—*i. e.*, either all to the right or all to the left—the 85 drawing Fig. 5 indicating the latter construction. By means of the rotation of the rollers *d* *e* in one direction the bunch *f* will be rotated in the opposite direction—*i. e.*, will be rotated toward the right, Fig. 4, when 90 the rollers rotate toward the left, or vice versa. The end of the cigar-wrapper *l* is now introduced through the open top of cover *a* between the "tip" ends *d'* *e'* of two of the adjoining rollers *d* *e*, hung in the cover. 95 Owing to the rotation of the rollers and the bunch, the wrapper will be gradually fed downward and wrapped around the bunch from its tip toward its stub. After this operation is completed the clutches are again 100 uncoupled by moving the frame *a* *b* away from the box *i*, Fig. 2, and the cover *a* is

swung up, so that the cigar, completely wrapped, may be removed and may be finished by cutting it off slightly at the stub end.

5 My improved machine not only rapidly wraps the bunch from tip to stub without injuring it, but shapes the same by exerting a uniform pressure against the bunch while being wrapped. In this way a superior well 10 drawing product of great uniformity is obtained in a quick and economical manner and without the use of skilled labor.

What I claim is—

1. In a cigar-machine, a series of rollers, 15 each having a gradually-expanded end and an abruptly-expanded end, combined with a series of intermediate rollers, each having a gradually-reduced end and an abruptly-reduced end, and means for simultaneously ro-

tating the rollers in the same direction, substantially as specified.

2. In a cigar-machine, the combination of a slideable divided open frame, with a series of rollers having expanded ends, a series of intermediate rollers having contracted ends, 25 clutches on the rollers, a box, shafts journaled in the box, clutches on the shafts adapted to engage the roller-clutches, a driving-shaft, and means for intergearing the driving-shaft with the clutch-shafts, substantially as specified.

Signed by me at New York city, Manhattan, New York, this 8th day of July, 1903.

ERNEST KUHNE.
